ELIAS JAFFE, OF NEW YORK, N. Y.

SELF-FASTENING BUTTON

Application filed March 28, 1929. Serial No. 350,545.

The present invention relates to improvements in that class of buttons which are to be attached to a garment without the use of thread and needle; and the invention has reference, more particularly, to a novel self-fastening button having integral prongs formed thereon for insertion through the fabric of said garment and adapted to be clinched against a suitable anchor member at the rear of said fabric, to thereby securely retain said button in fixed position upon said fabric.

The present invention has for its principal object to provide a simple, cheap, strong and secure self-fastening button, so constructed as to provide prongs struck outwardly from its back-plate and arranged in spaced relation at the periphery thereof for projecting through and securely clinching a fabric body between said back-plate and an anchor member at the rear thereof, said back-plate and cooperating anchor member serving to readily withstand all strains and pulls and forming a novel fastening means that cannot be torn accidentally from the garment by the most severe twisting, turning or pulling stresses.

Other objects of this invention, not at this time more particularly enumerated, will be clearly understood from the following detailed description of the same.

With the various objects of the present invention in view, the same consists, primarily, in a cup shaped back-plate to which is secured in overlying relation, the button-face shell together with its fabric covering when used, the bottom of said back-plate being inwardly concaved and having spaced prongs struck outwardly therefrom, said prongs being shaped and arranged so that the apertures, produced in said bottom upon the formation of said prongs, are not continuous but are bounded by metal portions extending from side to side of said back-plate, thereby providing a strong back-plate construction. Said prongs by being arranged at the periphery of said back-plate may be well spaced so as not to weaken the button supporting fabric by their insertion therethrough. These prongs are clinched upon an anchor member that is inwardly concaved to conform to the concaved bottom of

said back-plate, said prongs acting to cause said anchor plate to deflect said fabric inwardly against the bottom of said back-plate so as to be held in gripping relation therewith, the sides of the apertures in said back plate acting to assist in preventing relative movement of said fabric and said fastening means.

The invention is clearly illustrated in the accompanying drawings, in which:

Fig. 1 is a face view of the novel button of this invention attached to a piece of cloth or a portion of a garment;

Fig. 2 is a rear view of the structure of Fig. 1;

Fig. 3 is a vertical cross section of the novel construction of button, the same being taken on line 3—3 of Fig. 1, and being drawn on a considerably larger scale;

Fig. 4 is a vertical transverse section taken on line 4—4 of Fig. 1; and is drawn to the same scale as Fig. 3;

Fig. 5 is an enlarged view of the button shown in Fig. 1, but with the button-face shell and its covering cloth removed;

Fig. 6 is a view similar to Fig. 2 but illustrates a different form of anchor member.

Similar characters of reference are employed in all of the hereinabove described views, to indicate corresponding parts.

Referring now to Figs. 1 to 5 of the said drawings, the reference character 7 indicates the complete novel construction of self-fastening button made according to and embodying the principles of the present invention the same comprising a cup shaped back-plate having an inwardly concaved bottom 8 provided with angularly spaced sectorial apertures 9 uniformly spaced around the center portion of said bottom and arranged so as to provide metal portions extending from side to side of said back-plate. The sectorial apertures 9 are formed by striking outwardly V-shaped prongs 10 arranged diametrically opposite one another and projecting from the periphery of said bottom 8. The presence of the apertures 9 cause the bottom 8, in the preferred form, to have a cruci-form shape as viewed in plan, (see Fig. 5) and this conformation together with the concavo-convex shape of the bottom 8

in section cause this bottom to possess great strength and rigidity which is desirable in order for the bottom section to retain its effective grip upon the fabric 11 under all conditions of stress. It will be understood, however, that less or more than four prongs 10 and corresponding apertures 9 may be employed.

The prongs 10 have sharp points 12 which enable these prongs to be readily pressed through the body of the fabric 11 from the outer to the inner surface thereof. The portions of prongs 10 that project beyond the inner surface of the fabric 11 are adapted to be clinched over an anchor member 13. Anchor member 13 is of substantially annular shape and its diameter is less than that of the back-plate or bottom section so that it may be inserted between opposite prongs 10. The anchor member 13 is of concavo-convex cross-section and its inner convex surface 14 conforms to the concave under surface of the bottom 8. With the prongs 10 clinched upon the anchor member, this member presses against the inner surface of the fabric 11 underlying the bottom 8 and forces the outer surface of this fabric into intimate frictional contact with the bottom 8. Owing to the compression of the fabric by the anchor member, portions of this fabric are forced up into the apertures 9 causing the cruciform bottom 8 to be imbedded somewhat into the fabric, resulting in a greatly increased gripping action of the back-plate and anchor member forming the button bottom section or fastening means upon the fabric and serving to prevent the pulling out of the fabric from between the members 8 and 13 regardless of the forces applied to the button 7.

The back-plate is formed with a peripheral flange 16 extending upwardly from the bottom 8 and this flange has an outwardly offset upper portion 17 arranged in gripping relation with the button top section. This button top section comprises the button-face shell 15 having a covering cloth or fabric 18 which is tucked under the depending edges of the shell 15 and is retained in position thereon by the frictional grip of the flange 17. It is evident that the button-face shell 15 may or may not be covered with cloth and may be made in many ways and of many designs.

Referring now to Fig. 5, there is illustrated therein, a slightly modified form of anchor member. In this figure, the anchor member 20 is of substantially disk shape and has concavo-convex faces for conforming to the concave surface of bottom 8. This anchor member 20 is of substantially the same form as anchor member 13 with the exception that no central aperture is provided in member 20. The concave outer surfaces of anchor members 13 and 20 enable the prongs

10 to be bent into hook shape inwardly of the outer periphery of the anchor members (see Fig. 4) so that these prongs secure a better grip on the anchor members. The points 12 by being deflected inwardly are prevented from catching on or tearing clothing etc., that may be rubbed past the inner surface of the cloth or garment 11.

It will be noted that the novel self-fastening button of this invention is of simple construction, having two main parts, a top section comprising essentially the button-face shell 15 and a fastening means or bottom section comprising the back-plate and the anchor member gripping opposite sides of the fabric. Owing to the positioning of the prongs 10 at the periphery of the back-plate, these prongs may be well spaced so as not to weaken the fabric as a result of their insertion therethrough. Also, this construction enables the use of an anchor member of maximum area which together with the concavo-convex nature of these elements and the presence of the sectorial apertures results in an exceedingly rigid grip of the button or the fabric or garment. Also, since the prongs 10 extend over the outer periphery of the anchor member, a maximum area of fabric is gripped by the fastening means, thereby preventing the pulling out of the button and enabling the use of a disk shaped anchor member when desired.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:—

1. A self fastening button having a top section and fastening means therefor comprising, an anchor member, an apertured back-plate having outwardly struck prongs arranged around the circumferential periphery thereof, said prongs being adapted to extend through a supporting fabric and clinched radially inwardly over the outer peripheral edges of said anchor member, the apertures in said back-plate being produced upon the formation of said prongs, said apertures acting in cooperation with said prongs and said anchor member to secure said button to the supporting fabric.

2. A self fastening button having a top section and a bottom section, said bottom section comprising a cup shaped member having symmetrically arranged sectorial apertures in the bottom thereof, and V-shaped clinching prongs projecting from the circumferential periphery of said cup shaped member, said apertures being produced by the strik-

ing out of said prongs from the bottom of said member.

3. A self fastening button having a top section and a bottom section, said bottom section comprising a cup shaped member having sectorial apertures in the bottom thereof, said bottom being of concavo-convex shape, V-shaped clinching prongs projecting from the periphery of said cup shaped member, and an anchor member adapted to be clinched by 10 said prongs.

4. A self-fastening button having a top section and a bottom section, said bottom section comprising a cup shaped member having sectorial apertures in the bottom thereof, V-shaped clinching prongs projecting from the periphery of said cup shaped member at 15 the bottom thereof, and an anchor member, said prongs extending over the outer periphery of said anchor member and clinched 20 upon the exterior surface of said member.

5. A self-fastening button having a top section and a bottom section, said bottom section comprising a cup shaped member having a concavo-convex bottom with sectorial 25 apertures therein, V-shaped clinching prongs projecting from the periphery of said cup shaped member, said sectorial apertures being produced by the striking out of said 30 prongs from the bottom of said cup shaped member, and a concavo-convex anchor member conforming to the concave under surface of said cup shaped member and retained in cooperating relation with said under surface 35 by said clinching prongs.

6. A self-fastening button having a top section and a bottom section, said bottom section comprising a cup shaped member having a cruci-form bottom with a concave under 40 surface, an anchor member having a convex upper surface for cooperating with the concave under surface of said bottom to secure 45 said button to a supporting fabric, and lugs extending downwardly from the periphery of said bottom section and clinched inwardly over the outer peripheral edges of said anchor member.

In testimony that I claim the invention set forth above I have hereunto set my hand 50 this 13th day of March, 1929.

ELIAS JAFFE.
